CLAIM

The ornamental design for a radial seal filter, as shown and described.

DESCRIPTION

FIG. 1 is a top, left perspective view of the radial seal filter, showing the new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a bottom, left perspective view thereof.

The evenly spaced broken lines depict unclaimed parts of the radial seal filter and form no part of the claimed design. The appearance of any portion of the radial seal filter between the jagged break lines, regardless of length, forms no part of the claimed design.
